UNITED STATES PATENT OFFICE.

WILLIAM C. HEDGCOCK, OF CHICAGO, ILLINOIS, ASSIGNOR TO AMERICAN STEEL
FOUNDRIES, OF CHICAGO, ILLINOIS, A CORPORATION OF NEW JERSEY.

SIX-WHEEL TRUCK.

Application filed October 27, 1923. Serial No. 671,143.

To all whom it may concern:

Be it known that I, WILLIAM C. HEDGCOCK, a citizen of the United States, residing at Chicago, in the county of Cook and State of Illinois, have invented certain new and useful Improvements in Six-Wheel Trucks, of which the following is a specification.

This invention relates to six wheel trucks 10 for railway cars.

One object of the invention is to provide a simple, relatively light but durable six wheel truck in which the load will be evenly distributed.

Another object is to provide a simple and efficient six wheel equalizing truck adapted to meet the various requirements under service conditions.

These and other objects are accomplished 20 by means of the arrangement disclosed on the accompanying sheets of drawings, in which—

Figure 1 is a fragmentary top plan view of a six wheel truck embodying my invention;

Figure 2 is a side elevation of the same;

Figure 3 is a detached side elevation of the side frame equalizing bar;

Figure 4 is a side elevation of one of 30 the side frame members;

Figure 5 is a side elevation of the associated side frame member on the same side of the truck;

Figure 6 is a fragmentary sectional view 35 taken in the plane of line 6—6 of Figure 2; and

Figure 7 is a fragmentary sectional view taken in the plane of line 7—7 of Figure 2.

The various novel features of the in-

vention will be apparent from the following description and drawings and will be particularly pointed out in the appended 40 claims.

Referring to the figures of the drawings, 45 it will be noted that my invention is illustrated in connection with a six wheel truck, each side frame of which includes two operatively associated side frame members 10 and 11 in longitudinal alignment. The side 50 frame member 10 may be said to be a rigid side frame member and the side frame member 11 a trailing side frame member. The rigid side frame member 10 has secured to it in any suitable manner an outer journal 55 box 12 and an intermediate journal box 13.

The trailing side frame member 11 has secured to it in any suitable manner another outside journal box 14. Each of the side frame members 10 and 11 has a bolster opening 15 in which suitable load carrying 60 springs 16 are located, said springs being mounted upon spring seats 17 formed on said side frame members. Transverse bolster members 18 which rest upon the springs 16 are guidedly supported within said bolster openings 15. Any suitable bolster may be used, but I prefer to use a three piece bolster such as that shown in the Lamont Patent No. 1,377,706, granted May 10, 1921, in which an equalizing bolster unit 19 has 70 end girder members 20 rockably mounted upon the transverse bolster members 18. In this arrangement the truck center plate 21 is located directly over the middle axle 22, and the end axles 23 and 24 are spaced equal 75 distances from the middle axle 22.

It will be noted that the side frame members 10 and 11 are not directly connected to each other but are operatively connected to each other through, or by an equalizing 80 beam 25. The ends of this equalizing beam rest on top of the rigid and trailing side frame members at points directly over the bolster members 18 or at points equidistant between the axles. The equalizing beam is 85 secured against longitudinal displacement by upstanding lugs 26 which cooperate with shoulders 27 at the ends of said equalizing beam. Furthermore, said equalizing beam is secured against vertical displacement by 90 bolts 28 which pass through registering openings in the side frame members 10 and 11 respectively and in the equalizing beam 25. Preferably the equalizing beam is of channel section so that at its ends it may 95 overlap and inclose on three sides portions of the side frame members 10 and 11.

As stated, instead of the trailing side frame member 11 being directly connected to the side frame member 10, it is directly connected to the middle point of the equalizing beam 25. In this connection it will be seen that the trailing side frame member has a projecting arm 29 having an opening 30 which is made to register with openings 31 105 in the side flanges 32 of the equalizing beam for the reception of a bolt 33 which serves as a connection between the trailing side frame member 11 and the equalizing beam 25. This connection is vertically over the middle 110

journal box 13. A limited amount of clearance is allowed for lateral movement of the end of the trailing side frame 11 on the connecting bolt 33, and also a limited clearance for lateral movement of the equalizing beam 25 relative to the side frame members 10 and 11. The pivotal action of the side frame members 10 and 11 laterally in passing around curves may be considered as taking place at the point of connection between the rigid side frame member 10 and the equalizing beam 25. To facilitate vertical rocking of the side frames relative to each other, and relative to the equalizing beam 25, I have provided the equalizing beam with curved bearing surfaces 34 which, as mentioned before, rest upon the side frame members 10 and 11 between the upstanding projections 26. It will be noted that the holes 35 in the side frame members 10 and 11 through which the bolts 28 pass for connecting the equalizing beam 25 to said side frame members, are elongated to insure any thrust, due to relative longitudinal movement between said side frames, being taken by the lugs or projections 26 instead of by the pins or bolts 28.

By use of the equalizing beam, the stresses in the equalizing or trailing frame are simplified and also the size of the side frame members may be greatly reduced and production simplified and cost of production reduced, due largely to the fact that such side frame members can be produced with the regular processes and equipment used for producing the usual type of four wheel truck side frame.

It is my intention to cover all modifications of the invention falling within the spirit and scope of the following claims.

I claim:

1. In a six wheel truck, the combination of a side frame including two associated side frame members, means through which a load is transferred to said side frame members, and an equalizing member spanning said side frame members and through which one of said side frame members, is connected to the other side frame member.
2. In a six wheel truck, the combination of a side frame including a plurality of associated side frame members, means through which a load is transferred to said side frame members, and an equalizing member spanning and forming the sole connection between said side frame members.
3. In a six wheel truck, the combination of a side frame including a plurality of side frame members, bolster means through which a load is transferred to said side frame members, and an equalizing beam having two points of connection with one of said side frame members and only one point of connection to said other side frame member whereby said side frame members

are connected and the load evenly distributed.

4. In a six wheel truck, the combination of a side frame including a plurality of associated side frame members, a plurality of journal boxes connected to one of said side frame members and a single journal box connected to another side frame member, means through which a load is transferred to said side frame members, and an equalizing beam connected at a plurality of points to said side frame member to which a single journal box is connected and having a single point of connection to the side frame member to which two journal boxes are connected, whereby said side frame members are connected and the load equalized.

5. In a six wheel truck, the combination of a side frame including a rigid side frame member and a trailing side frame member, and a load equalizing member connected to one of said side frame members at a plurality of points and to the other side frame member at a single point for operatively connecting said side frame members and equally distributing the load.

6. In a six wheel truck, the combination of a side frame including a rigid side frame member, a trailing side frame member, and a load equalizing beam connected at two points to said trailing side frame member and at a single point to said rigid side frame member whereby said side frame members are operatively connected and the load equally distributed.

7. In a six wheel truck, the combination of a side frame including two associated side frame members, bolster members through which loads are transmitted to said side frame members, and an equalizing beam connected to said side frame members over said bolster members and having a second connection to one of said side frame members at an intermediate point along its length.

8. In a six wheel truck, the combination of a side frame including two associated side frame members, and a load equalizing beam connected at points equidistant from the center axle to said side frame members and having a second connection with one of said side frame members at a point along the vertical center line of said middle axle whereby said side frame members are operatively connected and the load equalized.

9. In a six wheel truck, the combination of a side frame including a rigid side frame member, a trailing side frame member, and a load equalizing beam connected to each of said side frame members at points equidistant from the middle axle and having a second connection with said trailing side frame member at a point above said middle axle for operatively connecting said side frame members and equalizing the load.

10. In a six wheel truck, the combination of a side frame including a rigid side frame member, a trailing side frame member having no direct connection to said rigid side frame member, bolster members located equal distances from the middle axle and through which a load is transferred to said side frame members, and an equalizing beam connected to each of said side frame members at points along the vertical centers of said bolster members, and a second connection to the trailing side frame member at a point in the vertical plane of said middle axle whereby said side frame members are operatively connected and the load equally distributed.
11. In a six wheel truck, the combination of a side frame including a plurality of associated side frame members, an equalizing member connecting said side frame members and having portions interengageable with said side frame members to take longitudinal shocks, the connection between said side frame members and equalizing member including a bolt operable in an elongated slot permitting said above mentioned interengageable portions to take the shocks.
12. In a six wheel truck, the combination of a plurality of longitudinally aligned side frame members having elongated slots
- therein and projections extending therefrom, and an equalizing member having means cooperating with said projections for taking longitudinal shocks transferred between said side frame members and equalizing member, pins connected to said equalizing member and passing through said elongated slots for connecting said side frame members and permitting said projections to take the shocks.
13. In a six wheel truck, the combination of a side frame including a plurality of associated side frame members, and an equalizing member connecting said side frame members, said equalizing member at its ends having curved seats for engaging said side frame members and permitting relative vertical movements therebetween.
14. In a six wheel truck, the combination of a side frame including a plurality of side frame members having no direct connection, and an equalizing member connected to said side frame members and forming a sole connection therebetween, said equalizing member having a channel section and embracing portions of both of said side frame members.

Signed at Chicago, Illinois, this 24th day of October, 1923.

WILLIAM C. HEDGCOCK.
